CLOTHES DRYER

Charles E. Jennings, Jr., 4020 Simon Road,
Youngstown, Ohio

Filed Sept. 25, 1963, Ser. No. 76,727

Term of patent 14 years

(Cl. D49—1)

FIG. 1

FIG. 2

FIG. 3

The back is substantially plain, the bottom is flat and plain.

I claim:

The ornamental design for a clothes dryer, as shown and described.
